UNITED STATES PATENT OFFICE.

WILLIAM BAKER, OF YOUNGSTOWN, OHIO.

SIEVE-PURIFIER.

1,032,104.

Specification of Letters Patent.

Patented July 9, 1912.

Application filed September 18, 1911. Serial No. 649,918.

To all whom it may concern:

Be it known that I, WILLIAM BAKER, a citizen of the United States of America, residing at Youngstown, in the county of Mahoning and State of Ohio, have invented certain new and useful Improvements in Sieve-Purifiers, of which the following is a specification, reference being had therein to the accompanying drawing.

10 This invention relates to sieve purifiers, and the object of my invention is to provide a purifying machine in which a continuous operation can be performed for expeditiously and economically purifying and 15 separating grades of middlings.

Another object of this invention is to combine parts of well known purifiers and separators to provide a self-contained machine that continuously uses its own air and there- 20 by obviates discoloration by air that is obtained from an outside source.

In all standard makes of sieve purifiers, the air is drawn from the outside of the machine through openings that are below 25 the sieve cloth. This air contains impurities that discolor the stock or material that the fan draws up with the air and discharges into the dust collector or cyclone. By repeatedly using one supply of air, the value 30 of the stock that is discharged from the dust collector or cyclone is materially increased in value, and this is accomplished by a combination of elements readily embodied in one machine that is easily controlled. With 35 this understanding of the broad principle of my invention, reference will now be had to the drawing and the detail description there- of. But in considering the detail description and drawings, it is to be understood that 40 the structural elements are susceptible to such changes, in the size, shape and manner of assemblage, as fall within the scope of the appended claim.

45 In the drawing:—Figure 1 is a longitudinal sectional view of the machine, and Fig. 2 is a plan of the same.

A machine in accordance with this invention comprises the casing 1 and in the forward end of said casing there is located a 50 conventional form of dust collector 2 prefer- erably of that type commonly known to the trade as the "cyclone" collector. Associated with this collector is a standard sieve purifier. The forward upper end of the casing 55 1 has a hopper 3 provided with an inlet pipe

4, and in the lower end of this hopper is a feeding device 17.

Arranged in the casing 1 is a reciprocating sieve 7 and this sieve is reciprocated or rocked through the medium of the eccentric 60 22 and a suitable source of power (not shown). The sieve 7 is suspended from transverse rods 22, but I reserve the right to use any suitable mechanism for reciprocating said sieve. The forward end of the 65 sieve 7 extends under the hopper 3 to receive the stock or material from said hopper that is spread upon the sieve surface in a thin sheet. The rear end of the sieve dis- 70 charges into a tail spout 11 carried by the end wall of the casing 1 opposite the end wall supporting the hopper 3.

The top of the casing 1 has a fan casing 23 containing a conventional form of fan 13 adapted to create a vacuum in the air chamber 10 above the sieve 7. The fan casing 23 has a flue 14 that extends over the top of the casing 1 and downward outside of the casing 1 and into the cyclone collector 2.

75 Between the top of the casing 1 and the sieve 7 there is a partition 24 provided with a plurality of valves 12 and these valves are regulated through the medium of handles 25 at one side of the machine. These valves regulate the amount of air that passes 80 through the material on the sieve 7. The cyclone collector is provided with a spout 5 by which the dust that is separated out of the air in the cyclone is discharged into a conveyer 6 located in the bottom of the cas- 85 ing 1. The material that passes through the sieve 7 is precipitated into a conveyer 9 lo- 90 cated in the bottom of the casing 1.

95 Arranged below the sieve 7 are carrying boards 16 to carry the material that passes through the sieve 7 down and over the tail of the cyclone collector and discharge the material into the conveyer 9.

100 Operation:—The stock or material fed on to the sieve 7 by the feeding device 17 is agitated upon the reciprocating sieve 7. The fan 13 maintains the circulation of air through the sieve 7 and the air lifts the fine impurities and dust out of the heavy par- 105 ticles. The fine dust and impurities are conducted by the flue 14 to the cyclone separator 2. It is in this separator that the action of air separates dust and impurities from the air and the pure air is discharged from the cyclone through the spout A into the casing 110

- 1 under the sieve 7. The pure air is again drawn through the sieve and the material upon the sieve, and this operation is continuously carried on whereby the air is freed 5 from dust and impurities. The dust and impurities, as fine bran, cell linings and germs that are intermingled with the air passing through the cyclone, when separated from the air, are discharged into the conveyer 6. The material that fails to pass through the sieve 7, on account of its size, is discharged into the tail spout 11, and the material that passes through the sieve is carried off by the conveyer 9.
- 10 15 I reserve the right to locate the cyclone separator at various positions within the casing 1, or even upon the outside of the casing, by providing suitable flues.
- It is thought that the operation and utility 20 of my machine will be apparent without further description, and that the machine can be used for other purposes than that herein specified.
- 25 What I claim is:—

- A machine of the type described comprising a casing, a sieve positioned within said

casing and dividing the casing into an upper and a lower chamber, a collector located in said lower chamber at one end thereof, stepped inclined carrying boards arranged 30 in the lower chamber directly over said collector, a fan mounted in the top of said casing, communicating with said upper chamber and adapted to produce a circulation of air through said sieve means for establishing 35 communication between said fan and said collector, a hopper at one end of the upper chamber, a discharge spout at the lower portion of the other end of the upper chamber, a conveyer mounted at the bottom 40 of said lower chamber, and a plurality of valves at the upper portion of said casing for controlling the circulation of air through said sieve and said collector, said valves positioned at each side of said fan and near 45 the upper end of said upper chamber.

In testimony whereof I affix my signature in the presence of two witnesses.

WILLIAM BAKER.
